METHOD AND MEANS FOR MANIPULATING
WIRE FORMED IMPLEMENTS

Friedrich Max Clauss, Bernville, and Carl Moellerke, West Reading, Pa., assignors to Textile Machine Works, Wyomissing, Pa., a corporation of Pennsylvania

Application July 29, 1938, Serial No. 221,900

35 Claims. (Cl. 163—1)

This invention relates to the method of, and means for, adjusting the positions of elements, as for presentation to an element working machine, and particularly to the adjustment of elongated elements, such as the blanks of needle like loop manipulating implements of knitting machines, about the longitudinal blank axes, and the insertion and withdrawal of the blanks relative to the device for effecting such adjustment.

One object of the invention is to provide the novel method of, and novel apparatus for, setting elongated metal blanks each having a portion to be adjusted as to a given lengthwise position, and angular position about the longitudinal axis thereof, for presentation to a mechanism for operation thereon.

Another object of the invention is to provide mechanism adapted to eliminate hand feeding in presenting elements, such as grooved needle blanks, to machines for operation thereon.

Another object of the invention is to provide apparatus, and the method, whereby the rate of feed of blanks, as above set forth, may be accelerated, to increase the output of such apparatus.

Another object of the invention is to provide the method of, and apparatus for, adjusting an elongated element or blank to a predetermined angular position about its longitudinal axis, by cooperation with an element or means on the blank locally disposed in a peripheral zone about said axis adapting the method and apparatus to such adjustment.

Another object of the invention is to provide means for rapidly transferring elongated elements or blanks from means for positioning the elements to means for working on the elements.

Another object of the invention is to provide the novel method of, and novel apparatus for, withdrawing individual elongated metal blanks from a bulk supply in accidental crosswise angular position and feeding the blanks to a positioning means adapted to successively turn each blank about its longitudinal axis to a predetermined crosswise angular position.

Still another object of the invention is to provide the novel method of, and novel apparatus for, transferring elongated blanks from means for adjusting the positions of the blanks about the longitudinal axes thereof to means for effecting working operations thereon, and whereby the adjusted positions of the blanks are maintained in transit.

A further object of the invention is to provide the novel method of, and novel apparatus for, withdrawing individual elongated metal blanks

from a bulk supply in accidental crosswise angular position, feeding the blanks to a positioning means adapted to successively adjust each blank about its longitudinal axis to a predetermined crosswise angular position, and successively transferring each blank so positioned from the positioning means to means for effecting working operations thereon and maintaining each blank in its adjusted position in transit.

10 Further objects of the invention will be in part obvious, and in part pointed out hereinafter.

The invention accordingly comprises the features of construction, operating steps, combinations of elements and arrangements of parts exemplified in the device hereinbelow described, and the scope of the application of which is indicated in the accompanying drawings, specification and claims.

In the accompanying drawings:

Fig. 25 is a fragmentary plan view of the parts immediately related to the angular positioning of the blank, the parts being in positions intermediate those of Figs. 21 and 22;

Figs. 26 and 26A to 29 and 29A, inclusive, are composite views diagrammatically illustrating several steps in the positioning of the needle blank, Figs. 26A, 27A, 28A and 29A showing certain of the parts, as viewed in Fig. 2, and Figs. 26, 27, 28, and 29, which are in greatly enlarged cross-section and are similar to Fig. 10, illustrating the positions of certain of the elements at the right of the figures;

Fig. 30 is an elevational view of a modified form of the invention;

Fig. 31 is an end elevational view taken from the left of Fig. 30, a portion of the structure being broken away;

Fig. 32 is a perspective view of certain of the elements at the topmost central portion of Fig. 30, slightly enlarged relative thereto;

Fig. 33 is a cross-sectional view taken along the line 33-33 of Fig. 34;

Fig. 34 is a cross-sectional view taken substantially along the line 34-34 of Fig. 30;

Fig. 35 is a cross-sectional view taken along the line 35-35 of Fig. 34;

Fig. 36 is a sectional view taken along the line 36-36 of Fig. 31; and

Figs. 37 and 37A to 40 and 40A, inclusive, are composite views, respectively, similar to Figs. 26, to 29A, inclusive, of the modified form of the invention.

Our invention includes the method of, and means for, both inserting and turning, or receiving and turning, into a predetermined angular position about its longitudinal axis, a blank including an element or holding surface providing for the automatic or semi-automatic adjustment of the blank to such position. Such holding surface or element may be a grooved portion of the surface of the blank adapted to receive a spring pressed finger, or a projection adapted to engage a dog or finger, between which and the blank there exists a condition of relative rotation, or a roughened strip adapted to engage a dog or finger having a roughened surface, or any of various other equivalents to resist relative turning movement between the blank and the means for turning it. Our apparatus has therefore, in one form, a rotatable member adapted to receive one end of an elongated blank, the rotatable member having associated therewith means adapted to permit the blank to turn with respect thereto, when the blank is held

against rotation, but adapted to turn the blank positively against a force tending to restrain its rotation when the turning means arrives at a definite angular relation to the blank, and has also means for turning the rotatable member through a certain angle more than a complete revolution when the blank has only a single element or means on its periphery at a local position thereabout having a holding surface or equivalent means. In case a blank has a plurality of such means locally about its periphery, it is necessary that the plurality of such local means be uniformly spaced around the periphery of the blank, and the minimum angular relative rotation between the blank and the rotating means permitted is 360°, divided by the number of holding surfaces or elements disposed locally around the periphery of the blank. Also, the means for producing relative rotation between the blank and the co-operating means includes means for stopping the blank in a given angular position about its longitudinal axis.

Although it is within the invention that the blanks may be inserted into, and removed from, the positioning mechanism by hand, and may thereupon, be transferred by hand to the machine for doing work thereon, or to a mechanical means for transferring the blank to the working machine, the invention also includes mechanical means for applying force to the blank to oppose its rotation by the positioning means, and means for inserting the blank into, and withdrawing it from, the rotatable member of the positioning means, as well as means for transferring the blank from the positioning means to the working machine. Such auxiliary means may be provided in connection with the positioning means, and one additional mechanism of simple character.

While it is within our invention that a blank may be presented by hand in position to be thrust into the positioning means by an automatic arrangement, we prefer to feed the blanks one at a time from a bulk supply into position to be taken into the positioning means and have disclosed and claimed a novel method and mechanism for this purpose.

The particular apparatus in accordance with the invention which is illustrated in the drawings is designed to operate on partially formed blanks for making knitting machine needles of the bearded type, the blanks having been grooved and reduced at one end to a very small gauge section of a length suitable for forming the beards.

While the press is illustrated in general and we do not make any claim of invention as to the press per se in this application, certain parts of the press are shown as cooperating in a novel manner with novel parts provided by us.

Forming part of the apparatus shown is a positioning means including a hollow head 1 of generally cylindrical outline mounted to traverse in a guideway 2 cut in the vertical face of a plate 3 and having reentrant or guiding edges 4 and 5 for supporting the weight of the head 1 by means of a wedge shaped extension 6 (Fig. 4) extending upwardly and laterally from the upper part of such head. A key 4a between the guiding edge 4 and the extension 6 is shown for assisting in holding the extension 6 in the desired position in head 1. The traversing action of head 1 in one direction is motivated from a main cam shaft 7 by means of cam 8 (Figs. 3, 4 and 6) at one end thereof which lies above and bears against a roller 9 journaled at point 9a on

a lever 10 so as to press the lever downward during a portion of its rotation. The lever 10 is pivoted, at one end, to the end of a fixed pin 11, by a screw and washer connection 11a. The other end of the lever 10 has an aperture 12 to receive a stem 13, the upper end of which is threaded to a connecting rod 14, and the lower end of which is provided with a ball 15 seated in a hemispherical socket in the lower face of the lever 10. The upper end of the rod 14 has a threaded connection with a stem 16, which extends upwardly, through an aperture 17 in an arm 18 (Figs. 2 and 5). The upper face of arm 18 has a socket, in which is received a ball 19 fixed to the upper end of the stem 16. Nuts 13a and 16a, on stems 13 and 16, respectively, are for fixing the stems in position relative to the rod 14. Downward motion, transmitted from cam 8 to the arm 18, through lever 10 and rod 14, turns a shaft 20, which is secured to the arm 18, in its bearing in a bracket 21 on block 3, and thereby turns an arm 22 which is fixed to the other end of the shaft 20. The lower free end of the arm 22 (Figs. 2 and 5) carries a roller 23 pivoted thereon, which is in bearing contact with plates held by lugs 24, integral with the head 1. The rocking of the arm 22 by the cam 8 therefore traverses the head 1 in the guide 2, to the right, as viewed in Fig. 5.

The return stroke or traverse of head 1 is caused by a spring 8a (Figs. 2 and 5) which is seated in a socket in a block 3a forming part of the frame work of the machine and lying in contact with plate 3. The thrust of spring 8a is transmitted to head 1 through a pin 8b which slides in a socket of the spring 8a, and bears, at one end, against the spring and, at the other end, against a socket in an arm 18a fixed to the shaft 20, at the same end as the arm 18, to form a bell-crank therewith. The spring 8a is under enough initial compression to hold pin 8b firmly against arm 18a and is further compressed when the cam 8 throws head 1 to the right. The spring therefore expands to throw head 1 to the left as soon as permitted by the contour of the revolving cam 8.

The positioning means of which head 1 forms a part is adapted to predetermine the crosswise angular position of an elongated metallic blank and includes rotating parts associated with said head. Within the head 1 is a hollow spindle 25 (Fig. 8) journaled therein and held against longitudinal motion with relation thereto by means of a pin 26 which has a head 27 within a recess of corresponding form within the spindle 25 and is fixed axially of the spindle by means of a collar 28 threaded into a counterbored opening in the end of spindle 25 and arranged to contact one of the flat sides of the head 27. The pin 26 is fixed to a plate 29 covering one end of the head 1 by means of a cross-pin 30. Plate 29 is fastened to the end of the head 1 by means of a set of screws 31.

The spindle 25 carries within it a means for engaging and turning a blank which it is desired to bring into a predetermined crosswise angular position. Such means is illustrated as comprising a tube 32 seated in the spindle 25 and extending into it from the right end thereof as viewed in Fig. 8. Tube 32 is fixed axially of spindle 25 by means of a screw 33 extending radially through the spindle 25 into a recess in the tube 32. When the parts are in assembled position screw 33 is prevented from working loose

by the fact that its outer end is covered by the head 1. The tube 32 has a longitudinal groove 34 therein within which is mounted a lever 35 pivoted on a pin 36 and having at its right end a radial projection 37 designed to fit into a groove 38 (Fig. 10) in a needle blank 39 which is held coaxially within the spindle 25. For supporting the blank 39 in position to be engaged by the projection 37, there is provided a small inner tube including a portion 40 having an aperture coaxial with the axis of rotation of the spindle 25 and the tube 32 and which is held in fixed angular position in the tube 32 by means of a set screw 41, which is prevented from working loose when the parts are in assembled position by the fact that the outer end of screw 41 is covered by tube 25. The inner tube portion 40 has a radial slot 42 therein so positioned as to receive the projection 37 and to permit it to reach the central bore of the inner tube portion 40 and to enter the groove 38 in the blank 39 whenever the plane of the projection 37 has been turned to coincide with that of the blank, provided the blank 39 has been pressed into the axial opening in the inner tube portion 40 to the proper extent so that the groove 38 in the blank overlaps the projection 37 in the axial direction. For determining the proper axial position of the blank 39 for this purpose we prefer to provide a block 43 which is pressed into an enlarged bore in tube 32 ahead of the inner tube portion 40 so that the block 43 comes up against a shoulder 44 formed at the junction of the enlarged bore and the remainder of the bore in the tube 32 whereby the block 43 forms a stop for the end of the blank 39 which has been inserted in the axial bore of the inner tube portion 40. Preferably, we form the inner tube in two parts or portions 40 and 40a having coaxial apertures therein. Tube portion 40a has a small bore, adjacent to the block 43, to accommodate and hold the smaller end of blank 39, and the bore of part 40a is enlarged at its juncture 40b with the bore of part 40 to avoid a shoulder on which the small end of the blank might catch. The lever 35 projects along the groove 34, to the left of the block 43, and is acted on by a spring 46 in such a way as to thrust the projection 37 into engagement with a blank 39 in the apertured tube 40. As illustrated, the spring 46 is held in a hole drilled along a diameter of the tube 32, and presses against the inner edge of the lever 35, spring 46 being held in position by the inner face of spindle 25.

Blank 39 is thrust into the parts 40 and 40a in any angular relation to the vertical. To position the blank 39 in a predetermined angular relation, the spindle 25 is rotated, while the blank 39 is held against rotation by its end outside the spindle, until the projection 37 is positioned over the groove 38. The spring 46 thereupon forces the projection 37 into the groove, and further rotation of the spindle 25 carries the blank therewith until the spindle is stopped at a fixed angular position, thereby placing the blank in a predetermined position.

Although theoretically, a 360° turn of the spindle 25 is sufficient, and may be practically sufficient in certain cases, to avoid possible discrepancies in construction and operation, or the results of lost motion, such as back lash of gear wheels, and the like, the spindle, in this instance, is turned one and a quarter revolutions, as a margin of safety, or leeway, in which to operate, which degree of angular motion need not be

exact, except as to its stopping position, and may vary several degrees either way. The initial positions of the spindle 25, and the projection 37, are shown in Figs. 10, 26 and 27 the groove 38 lying in tube portion 40 in any accidental or indefinite angular position which it may assume. The spindle 25 next rotates 45°, to the position shown in Figs. 11, 28 and 29 thereby, in the first 360°, necessarily inserting the projection 37 in groove 38, and in the next 90° carrying the blank 39 along, so that its groove faces downward. To rotate the spindle 25, for the purpose mentioned, a gear segment 47 (Figs. 1 and 4) may be provided, the teeth of which cooperate with gear teeth 48 on the spindle 25 (Fig. 9), the lower portion of the head 1 being cut away for a portion of the length of the head (Fig. 5) to provide for engagement of the gear segment 47 with the teeth on the spindle.

The gear segment 47 is carried at the upper end of an arm 47a, pivoted on a pin 49, and rocked about its pivot by a link 50 pivoted, at one end, to the lever 47a and, at its other end, to the upper end of a lever 51, the lower end of which is pivoted, coaxially with the lever 10, on the pivot pin 11. The lower end of lever 51 is held against sliding lengthwise of pin 11, by collars 11b, Fig. 6. The lever 51 is rocked, in one direction on its pivot, by a cam 52, as best shown in Figs. 6 and 7, to swing the gear segment 47, through a definite arc, sufficient to turn the spindle 25 more than 360°, to thereby move the spindle 25 to a predetermined angular position.

The cam 52 is shaped such that the gear segment 47 dwells for a certain length of time at the end of the stroke given it by the cam 52, so that the spindle 25, and a blank held thereby, are brought to a stop in a certain predetermined angular position, and held there for the blank to be withdrawn from the spindle.

As will appear more fully hereinbelow, the blank 39 is withdrawn from spindle 25 by holding it stationary during one of the traversing movements of the head 1 in which the spindle 25 is mounted. The return stroke of the lever 51, the link 50, and the arm 47a is effected by a spring 53, which is fixed, at one end, to the upper part of the lever 51 and, at its other end, to a pin 54 on the frame of the machine.

The apparatus illustrated in the drawings includes a means for cooperating with the traversing action of the head 1 both in introducing a blank into the spindle 25 of the positioning means and in withdrawing it therefrom. Such means as shown also grips one end of the blank while the other end is in the positioning means so as to provide a yielding resistance to the turning action of the spindle and the engaging means therein, as well as to transport the blank to the working means after it has been positioned and withdrawn from the positioning means. The arrangement illustrated for carrying out such functions comprises an arm 55 mounted to oscillate in a vertical plane about an axis 56 (Fig. 24). Arm 55 has a finger 57 thereon pressed against one face of the arm 55 by a leaf spring 57a, said finger and spring being shown as on the upper face of the arm when the free end of the arm is nearest the spindle 25 of the positioning means. An elongated metal blank such as 39 being held near the end of the arm 55 and the finger 57 and immediately above the free end of the arm 55, as illustrated in Figs. 20 and 25, when the head 1 is traversed in the direction toward the arm 55, the finger 57 presses against the larger end of the

blank 39 and forces the other end thereof into the spindle as far as permitted by the stop 43 as shown in Fig. 8. When the small end of the blank strikes the block 43 however, the larger end of the blank is then thrust under the finger 57 so that the blank is gripped between the finger and the arm 55 to apply a restraining force thereto resisting the turning of the blank about its longitudinal axis. As appears in Fig. 21, arm 55 has a shallow groove 55a therein to receive blank 39 and to help retain the blank 39 in proper position thereon and to increase the grip of the arm and finger 57 on the blank. The angular position of the groove 38 of blank 39, with respect to the spindle 25 and the arm 55, is entirely accidental when initially pressed into the spindle 25, as in Figs. 10 and 25. In general, the groove 38 of the blank 39 will not lie in the same plane as the projection 37. By the time the spindle 25 has turned somewhat, and necessarily by the time spindle 25 has made a complete revolution, the projection 37 is brought into the same plane as the groove 38, because the blank is held against rotation by the finger 57 and arm 55 whenever the projection 37 is not engaged with the groove 38. The projection is then forced into such groove, as shown in Fig. 11, by spring 46. After the projection 37 enters the groove 38, the blank is forcibly turned, in unison with the spindle, until they both reach a given angular position. The head 1 is moved by the spring 8a in the opposite direction to the travel of the head 1 when the blank entered the spindle 25; the blank 39 is withdrawn from the spindle by the grip had thereon by the arm 55 and finger 57 coincident with this operation of the head 1 by the spring 8a. The arm 55 is thereupon swung through an arc, from the position shown in Figs. 2 and 25 to the position shown in Fig. 22, to carry the blank 39 to a press 58 or other means for working the same, the finger 57 and arm 55 however continuing to grip it to prevent it from twisting on its longitudinal axis so that it arrives at the press in a desired predetermined angular position. The means for operating arm 55, and its adjuncts, will be described in detail hereinafter.

If the transfer arm 55 is omitted, the functions of this arm can be supplied by the hand of the operator who can readily hold the butt of the blank 39 while on a feeding means to force the blank into the spindle 25, and to apply a restraining pressure thereon during the positioning action of the spindle. Each of the three main devices, the blank positioning means, the transfer arm and the blank feeding means, hereinafter described, enables the speed of the press to be increased. The transfer arm 55 is therefore an important feature of the invention.

In the arrangement shown, the segmental gear 47 has a sufficient number of teeth thereon to rotate the spindle 25 one and one quarter revolutions, at each throw of the lever 47a, and the parts are so related that the spindle is stopped with the groove 38 in the needle blank facing directly downward at the end of the positioning movement of the spindle 25. The swing of the lever 55, through a vertical arc, thereby delivers the needle blank to the press 58, with the groove 38 therein facing upwardly, the position in which the needle blank is received by a press.

The press 58 (Figs. 21 and 22) includes a reciprocable blank holding member or finger 59 that is adapted and arranged to hold the needle 75 on the bed of the press in the position in which

it is placed thereon by the arm 55 and, when the finger 59 has engaged the blank 39, a rod 171a is thereupon brought laterally against the finger 57 to swing it out of engagement with the blank 39. The arm 55 is thereupon swung back into the position shown in Figs. 20, 21 and 25 in position to cooperate with the positioning of another blank.

While the blanks 39 can be presented to the arm 55 and the head 1 by hand, automatic means is provided for separating individual blanks from a bulk supply thereof, and for feeding them one by one into the position shown in Fig. 20. The mechanism for this purpose comprises a feeding means which includes a member or drum 60 (Fig. 12) mounted to traverse about a horizontal axis, and having grooves 62 therein parallel to the axis about which it moves. There may be a number of grooved sections coupled together, after the manner of a conveyor, or the grooves may all be in a member having a continuous surface, such as the drum 60 illustrated in the drawings.

One portion of the drum 60 moves upwardly into contact with a group 61 of elongated blanks, which rests partly on a narrow horizontal shelf 64. One upper corner of the shelf lies closely adjacent to the upwardly moving face of the drum 60, and, in part, on the lower end of an inclined plate 65 to which the shelf 64 is connected, the upper surface of the shelf forming a continuation of the upper surface of the plate 65. Blanks in the group 61 are so held as to facilitate the entrance of one blank in the group, into each of the grooves 62 in the member 60.

The surface of the drum 60 is of undulated form, as viewed in Fig. 12, from a point outside the drum, but on an extension of the axis thereof. The motion of the drum 60 therefore agitates the blanks in the group 61, and helps to ensure that each of the grooves 62 will receive a blank from the supply 61. Thus, the undulate surface of the drum 60 provides peaks 63 in which the grooves 62 are disposed. Also, the grooves 62 do not extend radially, in cross section, but are inclined to the radii to present the open sides thereof upwardly, on the upwardly moving face of the drum, toward the group 61.

To further ensure that a blank will enter each groove 62, as the groove passes upwardly beyond the shelf 64, magnetic means 66 is provided to urge the blanks in the group 61 against the outer face of the upwardly moving portion of the member 60. The means 66 may comprise a permanent magnet or, as illustrated, an electromagnet of the alternating-current type, having a pole portion 67 adjacent to the inner face of the drum 60, at a point close to the head of the drum, and another pole portion 68 axially at one side of the drum. The drum 60 is open at one end whereby the electromagnet extends into the drum, and conductors 66a, for supplying current thereto, extend through the open end of the drum (Fig. 17). The core of the electromagnet 66 is supported by the vertical plate 69, being secured to a block 70 (Figs. 13 and 17) fixed to the side of the plate 69 toward the drum.

The blanks to be fed are, in general, longer than the width of the drum 60, and guides 71 and 72 (Fig. 13) are provided for engaging the ends of the blanks which project beyond the grooves 62. As shown, the guides 71 and 72 have cylindrical surfaces, and are spaced somewhat axially from the drum 60 at opposite ends thereof. The guides 71 and 72 extend from a level, somewhat below the group 61, to a level above the axis of rotation of

the drum 60, the guide 71 being fixed, by screws 71a, to the plate 69, and guide 72 being fixed to a similar vertical plate 73 spaced from the plate 69, by screws 72a. The apparatus shown, being desired for working with metal blanks which are much smaller at one end than at the other, and it being desired to position the center of gravity of the blank generally centrally of the grooves 62, the blanks will project more at one end than at the other and the guide 71 designed to contact the tapered end of the blanks is made longer in the direction of the axis of the drum than is the guide 72. Further, if there is a greater length of the blank in contact with the guide 71, there is more tendency for such longer end to be displaced from the groove and we have placed the pole 68 of the electromagnet closely adjacent the concave face of the guide 71 to overcome such tendency by its pull on the blank. An alternating-current electromagnet is preferred in order not to magnetize the blank.

In order that drum 60 may not only feed blanks in between head 1 and arm 55 but may also hold the blanks stationary for the action of the head spindle 25 thereon, the drum 60 is given a step by step rotary motion by means of a pawl 74 (Fig. 18) which cooperates with a toothed ratchet wheel 75 on the shaft 76 of drum 60. Pawl 74 is mounted on a gudgeon pin 77 which is supported from the shaft 76 by a rocker arm 78. A spring 79 (Fig. 18) forces the pawl 74 into contact with the wheel 75, spring 79 being fixed to one end of a link 80 also pivoted to the gudgeon 77 at one end of the link, and spaced from rocker 78 by a washer 78a (Fig. 2). The other end of link 80 is pivoted to the upper end of a rocker arm 81 (Figs. 12, 16 and 18) by a pin 82. Arm 81 is pivoted to plate 73 by a pin 83 intermediate the ends of said arm and is rocked about its pivot by a cam 84, likewise on shaft 7 but centrally between the plates 69 and 73, arm 81 having a long pin 85 fixed thereto at its lower end and extending through a slot 73a in the plate 73 so that a roller 86 rotatably mounted at the reduced inner end of pin 85 by screw and washer connection 86a may contact with the surface of cam 84 to rock the arm 81. The motion of the arm 81 given it by the cam 84 throws the link 80 and pawl 74 in a certain direction to turn the wheel 75 and drum 60 in clockwise direction as viewed in Fig. 12. The return stroke of the pawl 74 is caused by a spring 87, one end of which is fixed to a pin on the link 80 and the other end of which is fixed to the outside of the plate 73.

In order that drum 60 may not overrun at the end of any feeding stroke of pawl 74 and may always hold the blank 39 accurately in position to cooperate with the positioning mechanism, the shaft 76 has a brake thereon comprising a split collar 76a (Fig. 12) fixed to plate 69 by screw 76b and a leather or similar liner 76c between collar 76a and shaft 76, said collar fixed to the plate 69 on the side toward plate 73. The friction exerted by the liner 76c can be adjusted as desired by screw 76d which extends across the split in collar 76a so that the drum will always stop at the angular position to which it is moved by a given stroke of pawl 75. As best shown in Fig. 17, screw 76b secures the collar 76a to boss 69a of the plate 69.

The group of blanks 61 is fed from a bulk supply 91 contained in a hopper H, of which the plates 65, 69 and 73 form the bottom and two sides respectively. The inner end of said hop-

per is formed by a vertical plate 88 (Figs. 12 and 15) which is parallel to the axis of drum 60 and is adjustably mounted on two heavy flanges 89, 89 formed integral with side plates 69 and 73. Flanges 89 are fixed in turn to the block or plate 3a by the through screws 3b which also serve to hold guide 3 in position. Vertical adjustment of plate 88 on said flanges is had by horizontal screws 89a set in holes 89b in plate 88 which are wider in the vertical direction than screws 89a and by vertical screws 88a in lugs 89c. Vertical adjustment of plate 88 by said screws determines the relation of the lower end of plate 88 to inclined plate 65. The lower end of the plate 88 is bent to provide a forked portion 90 which extends substantially perpendicular to the inclined inner side of the plate 65 and the lower end of portion 90 is spaced from plate 65 to provide a restricted outlet 92 (Fig. 19) for metal blanks held by the hopper H in said bulk supply 91. The inner side of the plate 65 has thereon a set of three thin ribs 93 (Figs. 13 and 16) which extend the full length of plate 65, beneath the end of the portion 90 and across the top of the shelf 64. Ribs 93 decrease the friction between the blanks in supply 91 and their support and permit them to feed down readily into the outlet 92. To prevent too many blanks from feeding into the group 61 and at the same time to avoid jamming of the blanks in the outlet 92, it is preferable to set the vertical width of outlet 92 by screws 88a so that it is not greater than twice the maximum diameter of a blank. Further, plate 65 has several apertures 94 therein adjacent the outlet 92 and a set of three tappets 95 (Figs. 3 and 13) is provided and arranged to move into the hopper through the apertures 94 closely adjacent the portion 90 to cut off the blanks in supply 91 from the outlet 92 from time to time and at the same time to agitate the blanks in and above the outlet. The tappets 95 are fixed to or form parts of a bar 96 (Fig. 14) fastened at the lower end of a pair of arms 97 (Figs. 12 and 16) the upper ends of which are pivoted on a pin 98 supported from the lower side of plate 65. The arms 97 and thereby the tappets 95 are actuated by a plate spring 99 so that the tappets tend normally to project into the bottom of the hopper through openings 94, spring 99 being shown as bearing at one end against a pin 100 extending between arms 97 and fixed at its other end to a block 101 in which the pin 98 is supported. In order to move the tappets 95 against the spring 99, the disc portion of cam 84, previously mentioned, has fixed thereto and on one side thereof, a segmental cam 102 (Fig. 14) the ends of which (Fig. 18) are curved in the opposite direction to the outer side of the disc 84. Further, shaft 7 of the cam 84 is so placed in relation to the bar 96 that the disc 84 projects within a notch 103 cut into the bar 96, and the point at either end of the segmental cam 102 is adapted to ride over a lip 96a on the bar 96 at the mouth of the notch 103 so that the action of the disc 84 and cam 102 flexes the spring 99 and pulls the tappets 95 down below the inner side of the plate 65. When the cam 102 passes out of contact with the lip 96a, spring 99 is thereby released and throws the tappets into the blanks in supply 91, Fig. 19. As is clear from Fig. 12, the blanks in bulk supply 91 and group 61 are parallel and it will be understood that the blanks are placed in the hopper H substantially parallel to each other and to end plate 88 and not only with their

smaller ends all in one direction, but with their out-of-round or grooved portions roughly in the same vertical plane. Further, the tappets 95 have their surfaces which contact with the blanks to agitate them so formed that their surface elements are transverse to the slope of plate 65 and substantially parallel to plate 88. The agitation of the blanks by tappets or agitating fingers 95, therefore, does not tend to throw the blanks out of parallelism with each other or with the aperture 92 at the lower edge of plate 88 through which the blanks leave the hopper H, but ensures that no bridging or wedging action will occur within the blanks in bulk supply 91 to prevent their feeding down through aperture 92 as space is made for fresh blanks in group 61. Moreover, as appears clearly from Figs. 12, 13 and 19, block 101 is fixed to plate 101a which is adjustably secured to the bottom of plate 65 by screws 101b which pass through openings 101c in plate 101a, said opening 101c being longer in the direction lengthwise of plate 65 than the diameter of screws 101b. By loosening screws 101b, the plate 101a and block 101 can be adjusted on the plate 65 by means of the elongated slots 101c provided in plate 101a for screws 101b, so that tappets 95 can be adjusted relatively to the end portion 90 and cam 102 so that the tappets will pass so close to end 90 as to produce an effective cut-off and escapement action on the blanks in supply 91 and the outlet 92 to ensure that the blanks in supply 61 shall be free most of the time from pressure due to the weight of the blanks in bulk supply 91 to thereby ensure that they will lie against drum 60 somewhat loosely to prevent wedging or jamming and to facilitate entry of blanks into grooves 62.

The hopper H, the drum 60 and the parts associated therewith, which contact the blanks 39 and which are within the range of the magnet 66, are preferably of a non-magnetic material, such as brass or the like, so that only the blanks 39 will be acted upon by the magnet 66.

Further, the action of pawl 74 is synchronized with that of the rotating motions of the angular positioning means and with that of the traversing motion of such means due partly to the fact that the cam 84 for the pawl is on the same shaft 7 as the cams 8 and 52 for the traversing and rotating motions respectively of the angular positioning means, while further means are provided, as in the case of the tappets 95, for final close adjustments. In the case of pawl 74, final close adjustment of its action is provided at the connection between the upper end of rock arm 81 and the link 80 at which point the arm 81 has an aperture 81b (Fig. 3) therein and set screws 81a which are threaded in opposite sides of arm 81 so as to bear against pin 82 to position it with respect to arm 81 so that the position of link 80 and pawl 74 and the timing of pawl 74 with respect to the other cams on cam shaft 7 may be adjusted finally by the screws 81a. Similarly, the final adjustment of the rotating motion of spindle 25 of the positioning means is provided for by the fact that the upper end of rock arm 51 has an opening 51c for the pin 51a larger than such pin and the set screws 51b are threaded into arm 51 and bear against pin 51a and may be adjusted to fix the pin to place it in the desired final position and timing with respect to the remainder of the mechanism by adjusting set screws 51b.

The timing and positioning of head 1 is finally

adjusted for synchronism with the remainder of the mechanism with which it cooperates by adjusting the effective length of the rod 14, and thereby the position of arm 22 and head 1 relatively to a given position of cam 8, by screwing threaded shanks 13 and 16 farther into or out of the rod 14 proper.

The cams 8 and 52, being used to actuate closely related parts, are conveniently placed close together on shaft 7. As best shown in Fig. 7, cam 8 is fixed to one face of a gear 104 by which cam shaft 7 is rotated and cam 52 is fixed to the opposite face of such gear. Gear 104 has a pair of through bores therein parallel to its axis, one threaded to receive screws 105 and 106 for securing the cams to opposite faces thereof and the other non-threaded to receive pins 107 and 108 to prevent relative turning movement between the cams and gear. Gear 104 also has a pin 109 through its hub and through shaft 7 whereby it drives the shaft.

The framework of the mechanism associated with the hopper H for the bulk supply of blanks has been mentioned and includes the plates 65, 69 and 73 forming part of said hopper. Plates 69 and 73 are tied together at the bottom, partly by being fastened to the flange 65a (Fig. 12) on bottom plate 65 by screws or rivets at points 65b, and are further tied together by a base plate 110 having vertical flanges 111, 111a, flange 111 lying immediately outside the plate 69 and flange 111a lying immediately inside of plate 73. The plates 69 and 73 are fastened by screws 112 to said flanges 111 and 111a. The flanges 111, 111a further have heavy arms 113 which extend along and reinforce the lower edges of the plates 69 and 73 where they overhang base 110 at the left of the base as viewed in Fig. 12, while flange 111 has a fork 211 (see Figs. 5 and 6) in which is fixed by a screw 212 the pivot pin 49 for the lower end of arm 47a. Fork 211 also carries pin 54 for holding one end of spring 53. Further a brace 3c (Figs. 2 and 4) extends inwardly and downwardly from one end of guide 3 to a point on fork 211. Plates 69 and 73 also are tied together as to their upper portions by the heavy plate or block 3a previously mentioned and to which the guide plate 3 and flanges 89 are secured by screws 3b. The pin 11 is fixed to plate 69 by a clamping nut 11c as best shown in Fig. 6.

The base plate 110 for the blank feeding and positioning mechanism is shown as set into a wide undercut notch 114 (Fig. 1), in the top of a bracket 115 and held in place by a plate 114a. Bracket 115 is fixed to a hollow base 116 on which are supported the press 58 and the arm 55, and within which most of the parts for operating said press and said arm are positioned. Fastened to one side of bracket 115 is a gudgeon 115a on which is journaled an idler gear 117 meshing with gear 104 on cam shaft 7 and with gear 118 on a second cam shaft 119 through which parts of the press 58 and the arm 55 are synchronized with spindle 25, but forming a part of press 58. Further, shaft 119 drives means for actuating the plunger rod 171a for releasing the blank 39 from the grip exerted thereon by finger 57 and arm 55 at the time such arm delivers the blank 39 to the press 58. Shaft 119 is journaled in and extends into said base casting 116, the mechanism and means contained therein being illustrated in Figs. 21, 22 and 23. The mechanism as a whole is driven by a motor shaft (not shown) geared to shaft 119 by a gear train 75

a portion of which is shown in dotted lines at 120 in Figure 1.

As will hereinafter appear more fully, the arm 55 is biased to the position shown in Fig. 21, but 5 the horizontal shaft 119 has thereon cam 121 (Figs. 21 and 23) which lies above a roller 121a in a fork at one end of a long lever 122, pivoted on rod 123 fixed to the frame of press 58 and associated with means about to be described whereby, as cam 121 pushes the lever 122 downwardly, the arm 55 is swung away from drum 60 into the position adjacent press 58 and shown in Fig. 22. The other end of lever 122 is pivotally coupled at 125 to one end of a second lever 124, lying above lever 122 for a portion of the length of the latter. Lever 124 is pivoted at a point intermediate its length on a rod 126, which also is fixed to the frame of the press and at its other end lever 124 is pivotally connected to a vertically acting plunger 127 (Figs. 23 and 24) for operating a rack member 130 which in turn operates arm 55. Plunger 127 is moved positively downwardly when cam 121 pushes downwardly on the end of lever 122 and the return stroke of 15 plunger 127 is caused by a spring 128 which is connected to lever 122 near cam 121 and to the inner face of the top horizontal web 116a of base 116 at point 129 and which serves also to hold the end of lever 122 up against cam 121. As best shown 20 in Fig. 24, the connection between plunger 127 and rack member 130 comprises an angular member 131 pinned to the upper end of member 127 and having a vertical extension 131a in which fits closely a horizontal pin 132 extending into an aperture 132b in an apertured lug 132a at the lower end of a member 133. Aperture 132b extends horizontally farther than the diameter of pin 132 and permits adjustment of rack 130 and arm 55 horizontally with relation to plunger 127. 25 The member 133 works in a vertical aperture 134 in rack 130 and the upper end of member 133 is connected to rack 130 by a spring 135 which has a slot and pin connection to member 133 at point 136 and has a pin connection to rack 130 at point 137. The rack 130 moves up and down in a guideway further described hereinbelow. Rack 130 has teeth 130a meshing with those of a pinion 138 which is cut integrally in a shaft 139 to which arm 55 is fixed and whose axis includes the point 56 previously mentioned as the pivot of arm 55. Shaft 139 has the transfer arm 55 fixed at one of its ends and is journaled in bearings 140 and 141 to prevent any tendency of arm 55 to twist out of its proper place of motion. 30 Shaft 139 has a conical enlargement 142 in bearing 141, bearing 141 having a corresponding taper to that of the shaft therein, so that the shaft 139 is thereby prevented from moving axially in one direction; and the end of shaft 139, outside bearing 140, has a collar 143 fixed thereon in contact with the outer face of bearing 140 to prevent movement of shaft 139 in the other direction. The plane of motion of arm 55 is, therefore, accurately fixed so that it cannot move out of the desired relation to the spindle 25 and/or the metal working means, when once its bearings have been correctly adjusted relatively to press 58 and head 1. 35

Further, a torsion spring 144 is coiled around the shaft 139, and has one end 144a held in an aperture in the bearing 140 and another end 144b held in an aperture in a collar 143a, fixed to the shaft 139. The torsion spring therefore, tends 40 to bias the teeth of the pinion 138 against the

teeth of the rack 130 in a counterclockwise direction as viewed in Fig. 24, so that in moving from the position of Fig. 22 to the position of Fig. 21, as the lug 132a contacts the bottom of rack 130, the arm 55 will immediately move in a counterclockwise direction, out of the plane of the blank 39 simultaneous with the movement of the rack 130.

It is clear from the foregoing that arm 55 is actuated by springs in both directions and, to ensure its correct angular relation to the spindle 25 and drum 60, as well as to the metal working device to which it delivers blanks, stops 145 and 146 (Fig. 24) are provided which contact with parallel faces 147 and 148 respectively of arm 55 to stop the arm at the ends of its strokes. The arc of motion of arm 55 is thereby determined to correctly position the arm with relation to the head 1 and the press 58. Due to the action of stops 145 and 146, the action of springs 135 and 144, and the contour of cam 121, the arm 55 is given a pronounced dwell at each end of its swing to facilitate the insertion of a blank under gripping finger 57 and the release of such finger from the blank.

The arm 55 and finger 57 grip the butt of the blank 39 between them due to the pressure of the spring 57a in the vertical plane which is the plane of motion of the arm. When, however, arm 55 has swung over as in Fig. 22 to deliver the blank to the press 58, it is necessary to release the grip on the blank and without twisting it about its longitudinal axis, which would disturb the angular position given the blank by the positioning means including head 1 and spindle 25. In order to accomplish such result, we have arranged in the apparatus shown that the horizontal blank holding member 59 of press 58 shall engage the blank before it is released by finger 57. The reciprocable member 59 is part of the press used for bending the beards and butts of grooved needle blanks and serves not only to prevent the blank from twisting, but as a platen about which the beard is bent, and cooperates with arm 55 to ensure that the blanks which have arrived at the press are maintained in the desired angular position. Arm 55 when in the position shown in Fig. 22 places the blank 39 in aligned shallow grooves not shown, but covered by blank 39 in Fig. 21 and formed in blocks 149 and 150 set one near each end of the position of the blanks in press 58 and embracing the jaws 152 of the press 58. While the needle is still held by the arm 55 and finger 57, the member 59 is pushed toward the left, as viewed in Figs. 21, 22 and 23, to engage the upward facing grooved-portion 38 of blank 39 and hold it against twisting about its longitudinal axis. The means for operating member 59 are best shown in Fig. 23 and comprises a cam 151 (Fig. 21) on shaft 119. Cam 151 pushes down periodically on a roller 153 (Fig. 23) journaled at one end of a horizontal lever 154 (Fig. 21) pivoted intermediate its ends on shaft 123. The other end of lever 154 is loosely pivoted at 155 to the lower end of a vertical plunger 156 about which is coiled a spring 157 which thrusts at one end against a loose collar 158 pressed by the spring against the under side of web 116a and at its other lower end against a shoulder 159 on the plunger, spring 157 serving therefore to produce the down stroke of plunger 156 and to hold roller 153 on lever 154 continuously in contact with cam 151. The plunger 156 extends up through web 75

116a, being suitably guided in 116a and other parts of base 116 and the upper end of 156 has a bevelled face 160 which bears against a complementary bevelled face on a block 161. The up-stroke of plunger 156 therefore pushes block 161 horizontally, the block being suitably mounted on an elevated portion 116b of base 116 for this purpose. As shown in Fig. 23 the block 161 moves toward the left on the up-stroke of plunger 156 and it is pushed to the right upon the down-stroke of said plunger by spring 162 which presses at one end against the left end of block 161 and at its other end against a pin 163 on said elevated portion 116b. In the position shown in Fig. 23, the plunger 156 is at the top of its stroke and member 59 is at the left in engagement with the upper surface of a blank (Fig. 21).

The block 161 has a clamp 164 fixed thereon composed of parts 164a and 164b which fasten holding member 59 adjustably to block 161 so that the member 59 has the same movement as the block. Clamp 164 being, however, on top of block 161 and the holding member 59 at the level of the upper portion of clamp 164, the member 59 is able to ride above block 149 to contact the top of the grooved part of a needle blank 39 thereon.

The above mentioned means for releasing finger 57 from blank 39 after the latter has been engaged by member 59 comprises a cam 165 on shaft 119 in contact with a cam roller 165a in a fork at one end of a rock arm 166 having a hub 167 (Fig. 23) intermediate its ends pivoted on a gudgeon 168 fixed in a boss 169 on part 116b. The lever 166 extends not only vertically but horizontally so that its upper end overlies one section of the elevated portion 116b of the base and it carries an adjustable contact screw 170 aligned with a two part horizontal plunger, the left portion 171 of which (as viewed in Figs. 22 and 23) is guided in an angle flange 172 fixed to the top of portion 116b and the right hand portion 171a of which is guided in lugs 173 formed on and projecting from one face of a casting in which rack member 130 is mounted and which will be more fully described hereinbelow. Plunger member 171 lies normally in contact with member 171a and acts, when thrust to the right by lever 166, to push part 171a to the right. A spring 174, one end of which is attached to a pin 175 on part 171a and the other end of which is attached to a pin 176 on one of the lugs 173, urges part 171a toward the left. At the point of contact with part 171a, the member 171 has a flange 171b to ensure contact with part 171a in case the two are placed somewhat out of alignment. Plungers 171 and 171a are best shown in Fig. 22 being partly broken away in Fig. 21.

The finger 57 which is operated in one direction only by the plunger member 171a is pivoted to arm 55 by pin 177 (Fig. 24), but somewhat loosely so that finger 57 has the necessary amount of play in the vertical plane to permit blank 39 to be inserted under it and to permit spring 57a to give finger 57 its gripping action. Pivot 177 is, however, in the vertical plane so that finger 57 may swing transversely of the vertical plane of motion of arm 55. Finger 57 also extends transversely of the plane of movement of arm 55 sufficiently so that it is normally held toward the left, with reference to such plane as viewed in Figs. 21 and 22, by a leaf spring 178 fastened to the right hand edge of the arm 55 so as to resist a movement of the finger beyond the right side of

arm 55. Finger 57, however, projects normally somewhat to the left of arm 55 and has a projection 179 on its left edge in alignment with the right hand end of plunger 171a. Consequently, when plunger 171a is thrust to the right, as viewed in Fig. 22, the finger 57 is also thrust to the right against the action of spring 178. In Fig. 22, the motion to the right of parts 171a and 57 has proceeded to the point that the end of finger 57 has released the butt of blank 39. An aperture 180 (Fig. 21) in finger 57 comes into the central plane of the arm 55 and a latch finger 181 (Fig. 24) on a latch lever 182 is thrust downward into the opening 180, arm 55 lying above finger 57 at the time. The lever 182 is mounted in a slot 182a (Fig. 24) in the central plane of arm 55 so as to pivot about a pin 183 (Fig. 24) and a leaf spring 184 is fastened on the face of arm 55 opposite the finger 57, so as to bear on the contact point 181a on lever 182 in alignment with finger 181 to press latch finger 181 against gripping finger 57 or through aperture 180 as the case may be. The finger 57 being latched in the position shown in Fig. 22, arm 55 is free of blank 39 and then swings back to the position shown in Fig. 21. As the arm 55 arrives at the position shown in Fig. 21, finger 57 is released from latch 181. This is accomplished by contact of a tappet finger 185, on the opposite end of lever 182 from fingers 181 and 181a, with a fixed pin 186. Spring 184 has an opening 184a (Fig. 22) therein through which tappet 185 projects so as to strike pin 186. Pin 186 is adjustable by being threaded into a flange 187 which lies be'ow the arm 55 and in which stops 145 and 146 are also adjustably mounted.

Flange 187 is part of a composite support including a casting 188 having a horizontal portion 189 of which flange 187 is a part. A vertical block 190 in which the guideway 191 for rack member 130 is cut is fastened to the transverse flanges 192 and 193 on part 188 in which bearings 140 and 141 are formed, the screws for fastening part 190 to 188 not being shown.

Plunger 127 for operating rack 130 is necessarily operated in fixed guides, but it is desirable to be able to adjust the position of arm 55 both in the direction of its axis, to aline it with the grooves in drum 60 and press 58, and in the direction at right angles to its axis to position the arm 55 to best advantage with respect to the head 1 and drum 60 at one side of its axis and the press 58 at the other side thereof. To provide such adjustments, we have mounted the casting 188 on top of a heavy vertical post 195 (Fig. 23) mounted for vertical adjustment in a block 196 by means of a pair of vertically aligned set screws 197, 197a in block 196 which bear respectively against the upper and lower bevelled edges of a wide horizontal groove 198 cut into the side of post 195. By adjusting screw 197 outwardly and screw 197a inwardly, the post 195 and arm 55 are lowered movement and, by reversing the adjustment of the screws, the post 195 and arm 55 are raised. The post 195 and arm 55 are fixed in the desired vertical position and also adjusted somewhat in angular relation to block 196 by a pair of screws 199, one of which appears in Fig. 23, and which bear against the bottom of groove 198. By adjusting the screws 199 in opposite directions, post 195 and arm 55 are adjusted angularly about the axis of post 195, while by setting up both screws 199 equally, post 195 and arm 55 are fixed against vertical and angular movement.

The block 196 in which post 195 is mounted is itself mounted in turn in a horizontal guideway 200 having reentrant sides and cut in the top of a block 201, a plate 200a being shown for retaining block 196 in proper alinement with the sides of the guideway 200. Block 196 can be adjusted in guideway 200, generally parallel to arm 55, by a screw 202 set in a bracket 203 fixed to one face of block 201. Further, block 196 and arm 55 can be adjusted in the horizontal plane in a direction at right angles to the arm 55 due to the fact that block 201 is mounted on an angle bracket 204, the vertical web 204a of which is fastened to part 116b of the base by screws 205, and the horizontal web 204b of which supports the block 201 and carries an integral arm 206 having an adjusting screw 207 therein at right angles to the screw 202 and arranged to force block 201 against a lug 208 also on web 204b. The shafts 119, 123 and 126 which form parts of the press are synchronized or kept in proper timed relation by gearing not shown.

After the arm 55 has been moved from its position of Fig. 22 to its position of Fig. 21, the drum 60 moves a step to bring a blank 39 intermediate head 1 and arm 55 to the position of Fig. 26A. The head 1 then moves to thrust the blank into the head and into the gripping portion of the arm 55 as shown in Figs. 27A and 28A after which the spindle 25 and the lever 35 are rotated relative to the blank 39 from the position of Fig. 27, until the radial projection 37 enters the groove 38 of the blank, whereupon the head and the needle continue to rotate to the position of Fig. 28. The head is next moved away from the drum 60 and the arm 55 as shown in Fig. 29A after which the arm is again swung over to its position of Fig. 22. Thereupon, after the needle blank has been engaged by the member 59 moving transversely thereof, the blank is released by the arm 55 and finger 57, and the blank is positioned longitudinally with respect to the press 58 by plunger 209, the beard is formed, the blank 39 is flattened by jaws 152, and the butt is bent, all by mechanism forming no part of the present invention. The process of feeding a blank forward by the drum 60 and the action thereon by the parts associated with head 1 and by arm 55 is then repeated.

It is within our process invention, however to maintain the head 1 or its equivalent entirely stationary and to insert and twist the blanks therein by hand. The groove 38, or other section of the blank having a holding surface, is thereby brought into predetermined angular position by engagement of the dog 37 with the holding surface of the blank. The dog 37 lying in a fixed plane in such case, the angular position of the blank is thereby determined and it can be removed from the head 1 and inserted into the press or other metal working means by hand with assurance that it will have the desired crosswise angular position and at a more rapid rate than if it were necessary to judge the angular position of the blank by inspection.

Wherever reference is made in the foregoing description or the appended claims to crosswise angular position it is intended to describe angular position of an elongated blank with reference to a plane passing through the longitudinal axis thereof. Moreover, where reference is made to lengthwise angular position, it is intended to describe angular position of an elongated blank with reference to a plane passing through an axis transverse thereto.

Figs. 30 to 40A, inclusive, illustrate a modified form of the invention, in which the means for positioning the elongated blanks is mounted on a base member fixed to the framework of the blank working machine, and the blanks are presented to the positioning device by a blank holding device mounted for longitudinal movement axially of the positioning means.

Referring particularly to Figs. 30, 34 and 35, a positioning device 250 comprises a hollow spindle 252, corresponding to the spindle 25 previously described, which is rotatably mounted in a sleeve 253 carried by a bracket or housing 254 secured to an upper plate constituting a portion of a base or frame 257 of the blank working machine.

The spindle 252 is held against longitudinal movement relative to the housing 254 by a plate 258 (Fig. 35) secured to the housing and abutting a shoulder portion 259 on the spindle. A gear wheel 262, secured to the spindle 252, is held in abutting relation to a second shouldered portion 263 of the spindle and the plate 258 by a nut 264 threaded on the spindle 252.

The spindle 252 carries a tube 267, fixed axially of the sleeve 253, as by a set screw 268, shown in Fig. 35. The tube 267 is provided with a longitudinal groove 269 (Figs. 37A and 40A) in which a lever 272 is mounted, as by a pin 273, for pivotal movement. The lever 272 is provided, at one end, with means, or an element, such as a fin like radial projection 274, arranged to enter a groove 275 of a needle-like blank 277 (Fig. 38A) for producing a loop manipulating implement of a knitting machine, similar to the needle blank 39 hereinbefore described, the grooved portion thus constituting means locally disposed in a peripheral zone about the longitudinal axis of the blank for cooperation with other means, such as the element 274, to resist displacement of the grooved portion and the element relative to each other about the blank periphery.

The blank 277 is supported in position, to be engaged by the projection of fin 274, in a bore, coaxial with the axis of rotation of the spindle 252, provided in a tube element 278 secured in the tube 267, as by a set screw 280. The tube 278 has a radial slot 279 therein through which the radial projection 274 extends into the bore of the tube element 278, whereby to enter the groove 275 of the blank 277, see Fig. 39A, when the blank has been positioned in the tube 278 a sufficient distance for the projection 274 and the groove 275 of the blank to be in radial register with each other. The projection 274, of the lever 272, is biased into the bore of the tube 278 and consequently into engagement with the blank 277 by a spring 283.

The above described elements, and the operation thereof are similar to the elements and operation herein described in connection with Figs. 8 to 11, inclusive.

To determine the angular position of the groove of the needle blank 277 about the longitudinal axis of the latter, the spindle 272 is given a predetermined rotative movement about its coincident axis by the gear wheel 262 secured thereto, through cooperation with an idler gear wheel 284 that is rotatably mounted on a stud 287 secured to the housing 254, the idler gear wheel in turn, cooperating with a driving gear wheel 288 that is secured to one end of a rotatable shaft 289 journaled in the housing. The shaft 289 has secured, at the other end thereof,

a gear wheel 291 cooperating with a rack 292 secured to the side of a member 293 that is slidably mounted in the base 257. The rack 292 and the member 293 are reciprocated by a lever 294 (Fig. 34) having, pivoted at one end thereof, a roller 296 disposed in a slot 297 that is defined by one end of the slideable member 293 and by two sides of a bracket 298 secured to the slideable member. The lever 294 is pivotally mounted on a shaft 299 that is pivotally mounted in a fixed bracket 302 on the base 251. Also fixed to the shaft 299, is a lever 303, one arm 304 of which carries a rotatable cam follower 307 for cooperation with a cam 308 mounted on a rotatable cam shaft 309 that is journaled in brackets 312 secured to the machine base 257. A second arm 313, of the lever 303, rotatably supports a cam follower 314 for cooperation with a cam 317.

The arms 304 and 313, and their respective cam followers 307 and 314, cooperate with the cams 308 and 317, which are provided with complementary contours, at opposite sides of the cam shaft 309, to provide the shaft 299 with positive action in both directions of its oscillatory movement. Also secured to the shaft 299, is a lever 318 which is provided with an adjusting screw device 319, (Figs. 33 and 34) held in adjusted position relative to the lever 318, by a set screw 320. One end of the device is arranged to engage a wear reducing insert 322 on the lever 294, and the other end is adapted to be engaged by a set screw 323 carried by an extension 324 of the lever 294. By locking the lever 318 between the insert 322 and the extension 324 on the lever 294, the lever 294 is positively oscillated with the shaft 299. To adjust the angular position of the lever 294 relative to the lever 318, the set screws 320 and 323 are disengaged from the adjusting screw device 319, which is then adjusted relative to the insert 322, after which the set screws 320 and 323 are tightened to lock the lever 294 to the lever 318.

The cam shaft 309 has secured thereto a bevel gear wheel 327 (Fig. 30) cooperating with a second bevel gear wheel 328 that is secured to a cam shaft 329. The shaft 329 is mounted in the base 257 transversely to the cam shaft 309, and is driven by means, such as a motor (not shown) which drives the cam shaft 309 through the bevel gear wheels 327 and 328.

A blank holding device 330 (Figs. 30 and 36) is provided for presenting the needle blanks 277 to the positioning device 250. The blank holding device 330 comprises a lever or clamp member 332 pivotally mounted on a bracket 333, as by a pin 334. The clamp lever 332 has pivotally mounted thereon, as by a pin 338, a self-adjusting jaw member 337 for clamping the blank 277 against a plate 339 that is secured to the bracket 333. The lever 332, and the jaw member 337, are biased toward the plate 339, by a spring 342, to clamp and hold one of the blanks 277, as it is moved toward the positioning device 250. The lever 332 is provided with an adjusting screw 345 which cooperates with the upper surface of the plate 339 to limit the movement of the jaw 337 toward the plate thereby to adjust the clamping action of the jaw on the blank 277.

The bracket 333 is adjustably mounted in a member 343 that is slidably mounted in an inverted T-shaped groove 344 formed by block-like members 347 and 348, and plates 349 and 352, the block-like members and the plates being secured to the upper plate portion of the base 257. The

holding device 330 is reciprocated to insert the blank 277 into the positioning device 250, and, after the groove of the blank has been turned to the proper angular position, retracts the blank therefrom.

For moving the holding device toward and away from the positioning device, there is provided a cam lever 353 that is pivotally mounted, as by pin 354, on a bracket 355 which is secured to the base 257. One end of the lever 353 is connected to a bracket 357 that is secured to slide member 343, by a link 358, and the other end of the lever carries a cam follower 359 for engagement with a cam 362 on the cam shaft 329, the lever 353 being biased into engagement with the cam 362 by a spring 363.

To release the clamping action of the lever 332 and the jaw 337 on the blank 277, the lever is provided with an extension 364 having a button-like element 367 mounted therein for engagement with a set screw 368 carried in one end of a lever 369 that is pivotally mounted on a pin 372 carried by a bracket 373 which is secured to the bracket 333. The other end of the lever 369 is provided with a pair of axially spaced cam followers 374 arranged to cooperate with a cam 377 which is slidably mounted in a groove 378 formed by extensions 379 of the bracket 333.

The cam followers 374 are mounted on the lever 369, as by a pin 382 extending through an opening 383 in a rod 384 which extends between the cam followers 374. The rod 384 is longitudinally slidably mounted in the bracket 333, and held by a set screw 387, mounted in an end thereof. A compression spring 388, surrounding the rod 384 in a bore 386 of the bracket 333, biases the followers 374 toward the cam 377, between a head 390 on the rod and a portion 391 of the bracket, which is held against a pair of bearing rollers 389 that are mounted in the groove 378 between extensions 379 of the bracket 333.

The cam 377 is actuated by a plunger 392 that engages a roller 393 mounted on the cam. The plunger 392 is raised and lowered by engagement of a rotatable cam follower 394 (Fig. 31) at the lower end of the plunger, with a cam surface 397 on a longitudinally reciprocable horizontal cam bar 398 which is slidably mounted in the base 257. The cam bar 398 is biased, by a spring 399, toward a cam follower 404 carried at one end of a lever 407, one end of the spring being secured to the cam bar, as by pin 402, and the other end being secured to the base 257, as by pin 403. The lever 407 is pivotally mounted on a shaft 408 that is carried in a bracket 409 secured to the base 257 of the machine. The other end of the lever 407 carries a cam follower 412 for engagement with a cam 413 that is mounted on the shaft 309.

In operation, the blank 277 is fed from a supply, as from the hopper H, hereinbefore described, to the receiving means, where it is deposited, near one end, into a slot 416 (Fig. 32) formed between a member 418 secured to a plate 419 and a member 421, carried by the bracket 333, and, near the other end, into a slot 420 of a device 422 (Figs. 30 and 34). The slots 416 and 420 guide the blank to position on the plate 339, of the blank holding device 330, and a shelf-like extension 423 of the guide device 422, see Fig. 30. 70

The cam bar 398 is moved to the left, from its position of Fig. 31, permitting the cam follower 394 to ride to the lowest point of the cam surface 397, thus removing the plunger 392 from engagement with the roller 393. This action

causes the followers 374, on the lever 369, to ride down the inclined surface of the cam 377, forcing the cam 377 downwardly, under the influence of the spring 388, thus moving the lever 369, in a counterclockwise direction about its pivot pin 372, as viewed in Fig. 36, to disengage the set screw 368 from the end of the clamp member 332, and permitting the spring 342 to bias the lever 332, and the jaw 337, toward the plate 339. 10 The blank holding device 330 and the blank 277 are moved from the position of Fig. 37 toward the positioning device 250 by the cam 362 and associated cam lever 353, one end of the blank entering the bore of the tube element 278 engaging the lever 272, thereby pressing the other end of the blank to position beneath the clamp jaw 337 and against a shouldered portion 340 of the plate 339, shown in Figs. 38 and 39, the blank holding device continuing toward the positioning device to move the groove 275 of the blank 277 in the axial direction into overlapping relation with the projection 274 of lever 272, see Fig. 38A.

The hollow spindle 252 and the lever 272 are rotated relative to the blank from the position of Fig. 38A, until, irrespective of the original position of the blank about its longitudinal axis, the radial projection 274 enters the groove 275 of the blank 277, and the action is continued until the spindle has been rotated a distance equal to one and a quarter revolutions, and stopped, and the groove of the blank is in the position of Fig. 39A. The holding device is next retracted, to the position of Fig. 40, the jaw 337 holding the positioned blank against the plate 339, and the cam 377 is raised, by the plunger 392, to move the lever 369, in a clockwise direction, thus raising the jaw 337 from the blank 277, to permit the removal of the latter from the holding device. 25 40 The spindle 252, or its equivalent, could, of course, be set at a definite position of origin, and either the spindle or the blank rotated to produce relative rotation between the spindle and the blank, whereupon, by cooperation between the element 274 and the groove 275, the blank is adjusted to a desired position.

Of course, the improvements specifically shown and described, by which we obtain the above results, can be changed and modified in various ways without departing from the scope of the invention herein disclosed and hereinafter claimed.

We claim:

1. In an apparatus for determining the angular and axial positions of elongated metal blanks, the combination of a rotary positioning means adapted to receive an end of an elongated blank, a member on said positioning means for engaging a section of a blank having a holding surface, means for holding the blank until said engaging member turns into a given angular position relative to the blank, said engaging member adapted to turn the blank against said holding means when once the engaging member lies in a predetermined angular relation to the blank, means to turn the positioning means at least 360 degrees and to stop it in a given angular position whereby the blank is brought into predetermined angular position and means associated with said positioning means arranged to axially move said blank to place it in said holding means.

2. In an apparatus for working elongated metal blanks, the combination with a working mechanism of means for withdrawing elongated blanks including sections having holding surfaces one

by one from a bulk supply of such blanks and for feeding blanks so withdrawn individually in accidental crosswise angular position, a positioning mechanism arranged to receive a blank from said means and adapted to engage said holding surface of the blank and to turn the blank in one continuous movement so that it is in predetermined angular position with reference to the vertical, and means to transfer a blank so positioned from said positioning mechanism to said working mechanism in predetermined angular relation to the angular position given the blank by said positioning mechanism.

3. In an apparatus for positioning elongated metal blanks, in combination, a spindle having an elongated axial recess, means on said spindle associated with said recess to engage a holding surface of an elongated blank lying in said recess when the engaging means is in given angular relation to the blank, and means for turning said spindle at least 360 degrees and for stopping it in a predetermined angular position.

4. In an apparatus for positioning elongated metal blanks, in combination, a spindle having an elongated axial opening adapted to receive the end of the blank, means on said spindle associated with said opening for engaging a holding surface of a blank when the two are in a given angular relation, means for turning said spindle at least 360 degrees and for stopping it in a predetermined angular position, and means for limiting the length of the portion of blank in said aperture at the moment of stopping said spindle.

5. In a transferring apparatus, in combination, means for engaging a holding surface of a blank and turning the blank to given position, an arm arranged to hold the blank during said turning and thereafter to swing through an arc, a finger on said arm for gripping the blank therebetween, a spring on said arm arranged to act in the plane of motion of the arm to press the finger toward the arm, a reciprocating member arranged to press said finger laterally to the arc of the arm to release the blank and means to return said finger to its first position after its release of the blank.

6. In a means for selecting and feeding elongated blanks from a bulk supply thereof, a drum having an undulating surface mounted to rotate on a horizontal axis, means to move said drum in a stepwise manner, grooves at the peaks of certain of the undulations on said drum, and means for holding a relatively small supply of blanks in contact with the upturning face of said drum somewhat below the level of the axis of rotation.

7. A method of separating and feeding elongated metal blanks from a bulk supply thereof comprising arranging a supply of blanks together in parallel relation, agitating said blanks by thrusting a stirring member into them at timed intervals, withdrawing blanks from said supply by gravity action, and picking them up and transferring them to a given location one at a time while maintaining their parallel relation to each other.

8. The method of feeding elongated metal blanks having holding surfaces comprising arranging a bulk supply of said blanks with their holding surfaces all approximately intersected by the same transverse vertical plane, withdrawing said blanks from said bulk supply into a smaller supply, feeding the blanks one-by-one with stepwise motion from said smaller supply along a given path while the blanks lie transversely to

their direction of movement along said path, and agitating the blanks of said smaller supply along said path.

9. A method of separating and feeding elongated metal blanks from a bulk supply thereof comprising arranging a supply of blanks together in parallel relation, agitating said blanks by thrusting a stirring member into them at timed intervals, withdrawing blanks from said supply and transferring them to a lesser supply at periods intermediate the times at which the blanks are agitated, maintaining said lesser supply in contact with a grooved member, and picking the blanks up from said lesser supply and transferring them one at a time in said grooved member to a given location.

10. In an apparatus for working elongated metal blanks, the combination of positioning means for engaging a holding surface of a blank and turning it into a given angular relation to the vertical, an oscillatory arm having means for engaging a portion of the blank not covered by said positioning means, and means associated with said oscillatory arm and said positioning means for releasing the positioned blank from the positioning means and for thereupon swinging said oscillatory arm to deliver the blank to a delivery position in a predetermined angular relation to the angular position given it by said means.

11. In an apparatus for working elongated metal blanks, the combination of a positioning means for engaging a holding surface of a blank and for turning the blank into a given angular relation to the vertical, an oscillatory arm having means thereon for gripping an end of said blank, means for producing relative motion of the said positioning means and said arm lengthwise of the blank to insert an end of the blank in said positioning means and an end in said gripping means and to release the blank from said positioning means, and means for swinging said arm to a delivery position with the blank in the desired angular position.

12. Apparatus for positioning an elongated blank about its longitudinal axis, comprising an element for holding cooperation with an element disposed at a local position peripherally on the blank, means for receiving the blank, means on said receiving means for determining the length of said blank to be received thereby, means for moving said receiving means to place said local element in cooperative relation to said holding element, means for moving one of said elements relative to the other about said axis until said elements are in cooperative engagement with each other and to move said cooperating elements to a definite location about said axis and stopping said movement at said location, irrespective of the positions of said elements relative to each other peripherally of the blank at the start of said movement.

13. Apparatus for positioning an elongated blank about its longitudinal axis, comprising an element for holding cooperation with an element disposed at a local position peripherally on the blank, means for receiving the blank, means on said receiving means for determining the length of said blank to be received thereby, means for moving said holding element to cooperative position with said local element on said receiving means, means for moving one of said elements relative to the other about said axis until said elements are in cooperative engagement with each other and to move said cooperating ele-

ments to a definite location about said axis and stopping said movement at said location, irrespective of the positions of said elements relative to each other peripherally of the blank at the start of said movement.

14. In fabricating a knitting machine loop manipulating implement, the blank of which has an element locally disposed about a peripheral zone thereof for holding cooperation with another element in said zone, the method of positioning said implement along and about its longitudinal axis, which comprises moving said element on said blank longitudinally into the zone of said other element, moving one of said elements relative to the other about said longitudinal axis until said elements are in cooperative relation to each other at a predetermined location, moving said elements together to a final predetermined location and stopping said movement at said final location whereby, irrespective of the positions of said elements about said axis at the start of said movement the blank will be moved to said location and said other element will stop said movement of the blank at said final location.

15. In fabricating a knitting machine loop manipulating implement, the blank of which has a longitudinal side groove element capable of receiving another element adapted to hold the implement against rotation about its longitudinal axis, means for positioning the implement about its longitudinal axis, means on said positioning means for determining the position of said blank along its longitudinal axis with respect to said positioning means, said positioning means comprising means for moving one of said elements relative to the other about said axis until said elements are in cooperative engagement with each other and to move said cooperating elements to predetermined location and stopping said movement at said location whereby, irrespective of the positions of said elements about said axis at the start of said movement, the blank will be moved to said location and said other element will be in said groove to stop said movement of the blank at said predetermined location.

16. In apparatus for determining a position of a blank about an axis thereof, the blank having means locally positioned on the periphery thereof about said axis for cooperation with means on another element resisting peripheral displacement between said means relative to each other, the combination of rotary positioning means adapted to receive a portion of the blank and including said element, means on said positioning means for determining the length of said blank to be received thereby, means for holding the blank until said element means turns to given position relative to the blank to effect said cooperation, said element means being adapted to turn the blank against the action of said holding means after said element means is turned to said cooperating position, and means for turning said positioning means more than 360° and for stopping the positioning means in a given position about said axis.

17. In an apparatus for determining the angular and axial positions of an elongated metal blank having a groove therein, the combination of a rotary positioning means adapted to receive an end of the elongated blank, a member on said positioning means for engaging in the groove of said elongated blank, means for holding the blank until said engaging member enters the groove of said blank, means to turn the position-

ing means at least 360 degrees whereby the groove of said blank is moved into a predetermined angular position and means associated with said positioning means arranged to axially 5 move said blank to place it in said holding means.

18. In an apparatus for positioning an elongated metal blank, having a groove therein, about and along its longitudinal axis, the combination 10 of a single positioning means adapted to receive an end of said blank, a member on said positioning means for engaging in the groove of said blank, means for holding said blank until said engaging member enters the groove of said blank, 15 means to turn the positioning means at least 360 degrees whereby the blank is turned about its longitudinal axis to bring the groove into a predetermined angular position, stop means on said positioning means for limiting the length of said blank therein and means for moving said positioning means along its longitudinal axis to engage said blank with said stop means.

19. In an apparatus for positioning an elongated blank, having a groove therein, about and 25 along its longitudinal axis, the combination of a single positioning means adapted to receive an end of said blank, a member on said positioning means for engaging in the groove of said blank, means for holding said blank until said engaging member enters the groove of said blank, 30 means to turn the positioning means at least 360 degrees whereby the blank is turned about its longitudinal axis to bring the groove into a predetermined angular position, stop means on said 35 positioning means for limiting the length of said blank therein, said positioning means being adapted to move said blank along its longitudinal axis to engage said blank with said stop means and to place it in said holding means.

20. In an apparatus for working elongated metal blanks, the combination of a single positioning means adapted to engage a groove in a blank and to turn the blank into a given angular relation to the vertical, means for moving said blank so positioned from said positioning means to a delivery position in a predetermined angular relation to the angular position given it by said positioning means, and means on said positioning means for moving said blank to place it in said moving means.

21. In an apparatus for positioning an elongated metal blank having a groove therein, the combination of a positioning means adapted to receive an end of an elongated blank, a member on said positioning means for engaging the groove of said blank, means for holding the blank, means for producing relative motion of said positioning means and said holding means lengthwise of the blank to insert an end of the blank in said positioning means and an end in said holding means and to withdraw the blank from said positioning means, means to turn the positioning means at least 360 degrees whereby the blank is turned to a given angular relation to the vertical, said holding means being adapted to transfer said blank to a delivery position in a predetermined angular relation to the angular position given it by said positioning means.

22. In an apparatus for positioning an elongated metal blank having a groove therein, the combination of a positioning means adapted to receive an end of an elongated blank, a member on said positioning means for engaging the groove of said blank, means for holding the blank until 70 said member engages in the groove of said blank,

means for moving said holding means lengthwise of the blank to insert an end of the blank in said positioning means and an end in said holding means and to withdraw the blank from said positioning means, and means to turn the positioning means at least 360 degrees whereby the blank is turned to a given angular relation to the vertical.

23. In an apparatus for operating on elongated metal blanks, the combination of a conveying means having a travelling member whose supporting surface is narrower than the length of the blanks to be carried thereby, means for operating said member step-by-step, means for supplying blanks to said member having an engaging portion, means on one side of said conveying means adapted to grip one end of a blank on the conveying means, and a turning means on the other side of said conveying means adapted to thrust a blank into engagement with said gripping means and also to turn the blank to a predetermined angular position.

24. In an apparatus for operating on elongated metal blanks, the combination of a conveying means having a travelling member whose supporting surface is narrower than the length of the blanks to be carried thereby, means for operating said member step-by-step, means for supplying blanks to said member having an engaging portion and in position to overhang the member at both edges, means on one side of said conveying means adapted to grip one end of a blank on the conveying means, and a turning means on the other side of said conveying means adapted to thrust a blank into engagement with said gripping means and also to turn the blank to a predetermined angular position.

25. In an apparatus for operating on elongated metal blanks, the combination of a conveying means having a travelling member whose supporting surface is narrower than the length of the blanks to be carried thereby, means for operating said member step-by-step, means for supplying blanks to said member having an engaging portion, means on one side of said conveying means adapted to grip one end of a blank on the conveying means, and a turning means on the one side of said conveying means adapted to thrust the blank into engagement with said gripping means and also to turn the blank to a predetermined angular position in a single continuous movement.

26. In an apparatus for operating on elongated metal blanks, the combination of a conveying means having a travelling member whose supporting surface is narrower than the length of the blanks to be carried thereby, means operating said member step-by-step, means for supplying blanks to said members having an engaging portion, a transferring means on one side of said conveying means and including a gripping means adapted to grip one end of a blank on the conveying means, a turning means on the other side of said conveying means adapted to thrust a blank into engagement with said gripping means and also to turn the blank to predetermined angular position and means to operate said transferring means to remove the blank from said travelling member to deliver it to a working station without angular movement between the blank and the transferring means.

27. The method of operating on elongated metal blanks comprising conveying blanks on a travelling member from which they project at least at one side, moving said member step-by-

step, turning each blank to a predetermined angular position by a single continuous movement while it lies at a given station, and swinging each blank from said station off said member and directly to another station at which an operation is performed thereon.

28. The method of operating on elongated metal blanks comprising conveying blanks on a travelling member from which they project at least at one side, moving said member step-by-step turning each blank to a predetermined angular position by a single continuous movement while it lies at a given station, swinging each blank from said station away from said member and directly to another station, and operating on both ends of a blank at said second station.

29. A method of making elongated wire formed implements comprising feeding elongated blanks one-by-one from a supply at regular intervals, advancing said blanks to a positioning station, turning each blank about its longitudinal axis while at said station and in a period not greater than one of said intervals to bring the blank to a predetermined angular position, swinging each blank to a second station, and operating on both ends of a blank at the second station.

30. An apparatus for operating on elongated metal blanks comprising a bulk supply of such blanks, a conveyor means travelling in a closed path and having transverse grooves, means whereby said blanks are moved from said supply to said grooves and so as to project therefrom, a transfer member along said path having a friction gripping means adapted to receive one end of a blank, a rotatable positioning member in alignment with said gripping means transversely of said path and adapted to receive the other end of a blank and to engage the blank for a turning operation, means whereby said rotatable positioning member is moved transversely of said path to thrust the blank into engagement with said gripping means, means whereby said member is turned at least 360° at one operation to turn a blank into a predetermined angular position while the blank is in engagement with said gripping means, means to withdraw said rotary member from the blank, and means to swing said transfer member to remove the blank from the conveyor means and to deposit the blank therefrom without relative angular movement between the blank and transfer member.

31. An apparatus for operating on elongated metal blanks comprising a bulk supply of such blanks, a conveyor means travelling in a closed path and having transverse grooves, means whereby said blanks are moved from said supply to said grooves and so as to project therefrom, a transfer member along said path having a friction gripping means adapted to receive one end of a blank, a rotatable positioning member in alignment with said gripping means transversely of said path and adapted to receive the other end of a blank and to engage the blank for a turning operation, means whereby said rotatable positioning member is moved transversely of said path to contact a blank and to thrust the blank into engagement with said gripping means, means whereby said member is turned at least 360° at one operation to turn a blank into a predetermined angular position while the blank is in engagement with said gripping means, means to withdraw said rotary member from the blank,

and means to swing said transfer member to remove the blank from the conveyor means and to deposit the blank without relative angular movement between the blank and transfer member, and metal working means arranged to receive the blank from said transfer member.

32. An apparatus for operating on elongated metal blanks having each an engaging portion comprising a bulk supply of such blanks, conveyor drum having an undulating surface narrower than the length of said blanks mounted to rotate on a horizontal axis and having grooves at the peaks of certain of the undulations thereof, means to move said drum about its axis step-by-step, means for agitating blanks in said bulk supply and for permitting them to move by gravity from said bulk supply into a lesser supply in which they rest against the undulating surface of said drum, magnetic means for drawing blanks into said grooves so as to project therefrom at an edge of said drum, a transfer arm on one side of said drum having a friction gripping means adapted to receive one end of a blank, a rotatable positioning member in alignment with said gripping means on the opposite side of said drum from said arm, and adapted to engage said engaging portion of a blank, means whereby said positioning member is moved toward said gripping means to contact a blank and to thrust the blank into engagement with said gripping means, means whereby said positioning member is turned at least 360° at one operation to engage the member with said portion of a blank and to turn the blank into a predetermined angular position while one end of the blank is held by said gripping means, means to swing said transfer arm to remove the blank from the conveyor means and to deposit the blank without relative

angular movement between the blank and transfer arm, and metal working means arranged to receive the blank from said transfer arm and to operate on both ends of the blank.

5 33. The method of positioning elongated blanks including sections having holding surfaces comprising placing a blank so that its holding surface is in a plane transverse to the blank and common to that of an engaging member and rotating said member at least 360° to bring said blank into a predetermined angular position in one continuous operation.

10 34. The method of positioning elongated blanks including sections having holding surfaces comprising placing a blank so that its holding surface is in a plane transverse to the blank and common to that of an engaging member, holding said blank while said member is rotated into engaging relation with said holding surface, rotating said member at least 360° to bring said blank into a predetermined angular position in one continuous operation and turning said blank through a vertical arc to transfer said blank to a delivery position in a predetermined relation to the angular position given it by said member.

15 35. In an apparatus for working elongated metal blanks, the combination of positioning means adapted to engage a section of a blank having a holding surface and to turn the blank into given angular relation to the vertical, means for holding said blank during said turning movement of said blank, and means for turning the blank so positioned from said means through a vertical arc to transfer it to a delivery position in a predetermined angular relation to the angular position given it by said positioning means.
